UNITED STATES PATENT OFFICE.

GUILLERMO TREJO, OF NEW YORK, N. Y.

LOCK.

Application filed August 10, 1923. Serial No. 656,677.

To all whom it may concern:

Be it known that I, GUILLERMO TREJO, a subject of the King of Spain, residing at New York, in the county of New York and 5 State of New York, have invented certain new and useful Improvements in Locks, of which the following is a specification.

This invention relates generally to locks, having more particular reference to a lock 10 for use on house-doors, the invention having for an object to produce a novel lock combining both the elements of key actuation and the making of a successive series of operations. 15 For further comprehension of the invention, and of the objects and advantages thereof, reference will be had to the following description and accompanying drawings and to the appended claims in which 20 the various novel features of the invention are more particularly set forth.

Fig. 1 of the drawings is a perspective view showing my improved lock.

Fig. 2 is a horizontal sectional view thereof, this view being taken on the line 2—2 of Fig. 3.

Fig. 3 is a longitudinal vertical sectional view taken on the line 3—3 of Fig. 2.

Fig. 4 is a transverse vertical sectional view taken on the line 4—4 of Fig. 2.

Fig. 5 is a transverse vertical sectional view taken on the line 5—5 of Fig. 2.

Fig. 6 is a horizontal sectional view indicating the door to which my improved lock 35 is applied.

As here embodied my improved lock comprises a rectangular casing 10 which is fitted in a suitable mortise in the door 11. Slidable in this casing is a bolt 12 which may be 40 projected through a suitable aperture in the end of the casing into the usual keeper element in the door frame 13. The bolt 12 has formed in the top thereof an elongated notch 15 which the bit of a key engages, this 45 key being adapted for insertion into the casing through the pairs of keyholes 16 and 17 formed in the front and rear walls thereof. The respective keyholes of each pair are spaced longitudinally from one another 50 and may be connected by slots 18 and 19, the slot 18 on the front or outer side of the casing being continued for a distance along the casing at 18' and terminating at its end in a third keyhole 20.

55 The keyholes 16 are covered normally by

a-shutter 25 which is hinged as at 26 to the top of the casing and is normally urged to closed position by means of the spring 27 coiled in a well known manner around the hinge pintle of the shutter. This shutter is 60 preferably sunk in a recess in the front wall of the casing so as to be flush with the latter. The shutter is normally held closed by two separate devices one of which comprises a spring latch 29 carried by the shutter and 65 engaging behind a lip 30 in the casing. The other comprises a bolt 31 slidably held in guides 32 on the shutter and having an offset end 31' adapted to engage behind the 70 said lip 30, a slot 33 being formed in the casing 10 in which the bolt is accommodated. This bolt has a laterally turned finger 34 on its upper end.

These two locking members are adapted 75 to be released by the key 35 which is used to move the main bolt, the end of the key being passed through the slot extension 18' at the side of the shutter with the bit 36 turned toward the latter. The bit is then pushed along the said slot behind the shutter and the key is then turned, the bit then engaging under the finger 34 on the bolt and lifts the latter. To enable the spring latch 29 to be lifted the key is formed with a separate handle element 35' which is screwed into a 80 suitable socket in the shank of the key and is provided with a pin projection 37 which is adapted to be pushed upward through a small opening 38 in the casing 10 to lift the latch from the lip 30.

As indicated in the drawings the bolt 31' is spaced slightly from its keeper element 30 when the shutter 25 is tightly closed so that when the catch 29 is released the shutter 95 may move sufficiently to pass the end of the latch over the lip 30 before the bolt 31 is released.

As will be apparent, the keyholes through which access can be had to the bolt to shift the latter are covered on the outer side of 100 the door by the shutter. To give notice if an attempt is made to insert a key or a picking tool through the exposed slot 18' or key-hole 20 a plate 40 is mounted in the casing behind said slot and carries a contact member 41 adapted to engage a fixed contact member 42 to close a circuit to a bell or other signal if the plate is pushed inward in the casing. This plate is mounted for 105 transverse movement in the casing on the 110

guide members 43 and is normally pressed forward by means of expansion springs 44 bearing thereon.

To lock the door from the inside without the use of the key a spring pressed stud 50 may be mounted in a vertical slot 51 in the inner wall of the casing 10 and may be adapted to detachably engage in a suitable socket in the bolt 12.

10 It is believed that the manner of action of my improved lock will be readily understood from the above description. The key cannot be inserted for engagement with the bolt until the shutter 25 is opened and in order to do this the latch 29 must first be raised, and then the bolt 31 lifted.

15 Having thus described my invention what I claim as new and desire to protect by Letters Patent of the United States is as follows:

20 1. In a lock, a casing having a number of keyholes in the face thereof united by a slot, a bolt, a shutter covering the keyhole

through which access is had to the bolt, a locking element applied to the shutter, said locking element being accessible for release by the key for releasing the said bolt when the said key is inserted into the said slot.

2. In a lock, a casing having a keyhole, a hinged shutter closing said keyhole, and a pair of locking elements holding said shutter closed, said locking elements being arranged for operation in a certain sequence to release the said shutter.

3. In a lock, a casing having a keyhole, a hinged shutter closing said keyhole, and a pair of locking elements holding said shutter closed, said locking elements being arranged for operation in a certain sequence to release the said shutter, one of said locking elements consisting of a spring latch and the other of a sliding bolt.

35 In testimony whereof I have affixed my signature.

GUILLERMO TREJO.
